UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

DIE FOR TRIMMING BLANKS.

1,294,990.

Specification of Letters Patent. Patented Feb. 18, 1919.

Application filed July 12, 1918. Serial No. 244,540.

To all whom it may concern:

Be it known that I, RICHARD LESTER WILCOX, a citizen of the United States, and a resident of Waterbury, county of New Haven, State of Connecticut, have invented certain new and useful Improvements in Dies for Trimming Blanks, of which the following is a specification.

My present invention relates to improvements in dies for giving a trimmed cross-section to a blank as is done, for instance, in forming the square, hexagonal or octagonal shapes of bolt heads, nuts, and the like, or a many sided shape of any kind such, for instance, as a circular section with flat sides as is formed on shackle bolts and the like. It will be understood that by "polygon" or "polyagonal" I mean any such shape. A blank may also be cut so as to have a circular section.

One of the objects of my invention, among others, is to produce a die which will be easy to construct and at the same time easy to sharpen in a simple manner. Another object of my invention is to produce such a die which will be capable of adjustment.

In the accompanying drawings Figure 1 represents in perspective an illustrative form embodying my invention;

Fig. 2 is a cross-section in elevation through the die illustrated in Fig. 1 taken on the line 2—2;

Fig. 3 is a plan view of a modification, in which some of the parts are adjustable.

The corresponding parts are referred to both in the drawings and in the specification by similar reference characters.

Referring to Figs. 1 and 2, the form of die here illustrated is of the solid type, being made of a single piece of metal. Extending through the die from top to bottom is an opening 10 which, in this particular instance, is such that its cross-section is an equilateral hexagon. The top surface 11 of the die is preferably turned conically and the intersection of this conical surface with the edges of the opening 10 produces cutting edges.

In some cases it is desirable that the cutting edges be shaped in such a way that the article to be trimmed will be cut angularly as the die and the article move relatively to each other along the axis of the opening 10. This is accomplished by making some

of the cutting edges so that one point of such edge is higher above the base of the die than another. Such an arrangement is provided in my copending applications, Nos. 219,170 and 219,172, each filed February 26, 1918, but I have found that angular cutting edges of this type may be more readily produced by providing around the top surface of the die a series of substantially flat surfaces 12 which make acute angles with the axis of the opening 10, and preferably with the surfaces arranged so that they are in effect the sides of a pyramid, in which case each surface will form a right angle with the plane passing through the axis of the opening 10 and through the center line of the surface. With the cutting edges formed by such surfaces the die may be readily sharpened by passing a grinding wheel across these substantially flat surfaces.

The angular cutting edges may be formed in several ways by the surfaces 12. If the opening 10 is circular in cross-section, then obviously the spacing of the surfaces 12 around the opening 10 is more or less immaterial, although it is preferable that they be so arranged that they join each other at the edge of the opening. By so doing all parts of the cutting periphery of the opening will have a direction angular to the axis of the die. When the opening is polygonal in cross-section, I preferably arrange the surfaces 12 so that two adjacent cutting edges will form an angle at their intersection. In this way, one of such pair of cutting edges will throw its chip to one side of the axis of the die while the other edge will throw its chip in the opposite direction. This may be accomplished by forming the surfaces 12 so that each will contain one of the apexes or angles of the polygon.

When the opening 10 is an equilateral polygon, such as the cross-section of the usual square or hexagonal bolt head or nut, the preferable form of angular cutting edges may be provided by arranging the surfaces 12 as shown in Fig. 1; that is, with the surface broad enough at its intersection with the periphery to include two sides of the hexagon and with the surfaces 12 meeting each other at the apexes or angles of the hexagon. An inspection of Fig. 1 will show that each of the cutting edges thus formed will have an angular approach to the article

passing through the opening 10 toward the base, each adjacent pair of cutting edges having an opposite angle of approach.

The cutting edges may also be formed by 5 providing as many surfaces 12 as there are sides to the polygon, but with the surfaces joining each other between the apexes or angles of the polygon. Thus, in the die shown in Fig. 1, with the equilateral hexagonal opening 10, surfaces could be provided, each with one of the angles of the hexagon lying between the outer limits thereof and such surfaces joining each other midway, for instance, one of the sides of the 15 hexagon.

It will be understood that, while preferably I make the surface 11 conical, which facilitates its manufacture, this top surface 11 may be almost any shape, because obviously it performs no function in the cutting operation. It might readily, therefore, be, for instance, at right angles to the axis of the die, in which case the surfaces 12 would be cut below the level of the top 25 surface of the die.

For many purposes, and particularly when used in connection with the method illustrated in my copending application No. 219,170, it is desirable that the opening 10 shall extend completely through the die, although for many purposes this is not 30 necessary.

For some purposes, it is desirable to provide a die with independent cutting edges, such as shown in Fig. 3 which, as will be understood, is precisely the same as illustrated in Figs. 1 and 2, except that the cutting edges are formed on separate pieces of steel 14, which in the form illustrated in 35 Fig. 3 are shaped as the frustums of pyramids, the tops of which form the sides of the opening 15 and the bases contact with a hexagonal opening in the body member 16. The members 14 are held in place by screws 40 17. The arrangement thus described is similar to that of the copending application of Wilcox and Nolan, No. 219,173, filed Feb. 26, 1918, and form no part of my present invention.

50 The cutting edges around the opening 15 may be formed as already described for the arrangement shown in Fig. 1, by providing a plurality of substantially flat surfaces 18 in such a way that these edges in the preferred form will have an angular approach to the blank being trimmed as it passes the cutting edges. It will be understood that the arrangements of Figs. 1 and 3 are precisely the same, except that in Fig. 3 the die 55 is made in parts so that the cutting edges are located on separate members instead of on the solid die. All of the modifications heretofore suggested as to the form shown in Fig. 1 apply equally well to the form 60 shown in Fig. 3.

I claim—

1. A die having an opening therein and a plurality of substantially flat surfaces on the top face of the die, the planes of such surfaces making acute angles with the axis of the opening and intersecting the edges of the opening to form a series of cutting edges in the periphery thereof, each of the surfaces forming a right angle with the plane passed through the axis of the opening and intersecting the surface at its center line. 70

2. A die having an opening therein and a plurality of substantially flat surfaces on the top face of the die, the planes of such surfaces making acute angles with the axis of the opening and intersecting the edges of the opening to form a series of cutting edges in the periphery thereof, the surfaces meeting each other at the periphery of the opening, each of the surfaces forming a right angle with the plane passed through the axis of the opening and intersecting the surface at its center line. 80

3. A die having an opening therein and the top face of the die sloping away from the periphery of the opening, and a plurality of substantially flat surfaces on the top face with their planes making acute angles with the axis of the opening and intersecting the edges of the opening to 90 form a series of cutting edges in the periphery thereof.

4. A die having an opening therein and the top face of the die sloping away from the periphery of the opening, and a plurality of substantially flat surfaces on the top face with their planes making acute angles with the axis of the opening and intersecting the edges of the opening to 100 form a series of cutting edges in the periphery thereof, the said surfaces meeting each other at the periphery of the opening. 105

5. A die having a polygonal opening therein and a plurality of substantially flat faces on the top face of the die, the plane of each of such faces making an acute angle with the axis of the opening, and each of such faces intersecting the opening so that one of the apexes of the periphery 110 is between the outer edges of the surface where it intersects the periphery of the opening. 115

6. A die having an equilateral polygonal opening therein and a plurality of substantially flat faces on the top face of the die, the plane of each of such faces making an acute angle with the axis of the opening, and extending across two of the sides of the polygonal opening where said faces intersect the opening, to form a series of cutting edges around the periphery of the opening. 120

7. A die having a conical top face and an equilateral polygonal opening therein and a 130

plurality of substantially flat faces on the top face of the die, the plane of each of such faces making an acute angle with the axis of the opening, and extending across 5 two of the sides of the polygonal opening where such faces intersects the opening, to form a series of cutting edges around the periphery of the opening.

8. A die comprising a body member and 10 a plurality of cutting members held therein, each of the members having a cutting edge

and the members being constructed and arranged and held in the body member so as to form a polygonal opening therein, with 15 the cutting edges forming the periphery of the opening, the die being provided with a plurality of substantially flat surfaces making acute angles with the axis of the opening and intersecting the opening at the cutting edges, with the cutting edges lying in 20 the said surfaces.

RICHARD LESTER WILCOX.
